J. Sherwood

Windlass Water Elevator,

N° 35,113.

Patented Apr. 29, 1862.

Inventor;

James Sherwood

UNITED STATES PATENT OFFICE.

ISAAC SHERWOOD, OF UNADILLA, NEW YORK.

IMPROVEMENT IN WATER-ELEVATORS.

Specification forming part of Letters Patent No. 35,113, dated April 29, 1862.

To all whom it may concern:

Be it known that I, ISAAC SHERWOOD, of Unadilla, in the county of Otsego and State of New York, have invented a certain new and useful improvement in the construction of apparatus for drawing water, by means of which a rotary is converted into a reciprocating movement for the purpose of alternately letting down and lifting up a bucket or buckets; and I do hereby declare that the following is a full and true description thereof, reference being had to the accompanying drawings and the letters and figures of reference marked thereon.

Figure 1 represents a front elevation of the apparatus. Fig. 2 is a plan of the same. Figs. 3, 4, 5, and 6 are views of the gearing in different positions.

A and A² are spools respectively attached to the shafts B and B², resting on bearings in the frame C C and geared together by the cog-wheels D and D², having an equal number of cogs and therefore producing a uniform motion in opposite directions. The wheels D and D² lie in different, though parallel, planes of motion, but overlap each other's faces sufficiently to firmly and constantly interlock, as shown in Fig. 2 and also in Figs. 4, 5, and 6.

Motion is communicated to the spools by the toothed wheel E upon the shaft F, having its bearings attached to and elevated above the frame C C and rotated by a crank or other driving gear. This wheel E, with its shaft F, has a lateral sliding movement in these bearings, by means of which it may be made alternately to gear with either D or D², so as to reverse their motion, or may be made to gear with both at the same time in such a way as to lock them and prevent a motion of either. As each bucket approaches the termination of its upper movement it strikes the arm G or G² of the lever H, pivoted at I to bearings upon the frame C C. The upper arm of the

lever H grasps the wheel E between the forks K and K², and by means of the elbow-joint at I the motion communicated by the bucket striking the lever G or G² is converted into a lateral sliding movement of the wheel E and its shaft F, the object or effect of which is to cause the wheel E to gear both with D and D² at the same time in such a way as to lock them and prevent a motion of either. In this way, where two buckets are used one is held stationary while being emptied and the other is kept under water and permitted to fill.

The advantages of my invention are that I am enabled to raise and lower the buckets alternately by a uniform motion of the shaft F in one direction; that I am enabled to make the spools A and A² and also the gearing-wheels of different sizes, as I may wish to obtain different degrees of power or velocity, or as convenience may dictate; that the lateral sliding movement of the shaft F with the wheel E may be communicated by the strike of each bucket as it approaches the termination of its upward journey, and that by causing the wheel E to gear with both D and D² at the same time the latter may be locked and the motion of either checked and the bucket and its contents held at rest without ratchet or pawl.

I claim as my invention and desire to secure by Letters Patent—

1. A water-elevator having in combination the wheels D and D² and E, constructed and operating substantially as above described.

2. In combination therewith the double-acting lever G and G², H K K², constructed and operating substantially as hereinbefore described.

ISAAC SHERWOOD.
